CLOSURE-LOCKING MEANS FOR GAS-RETORTS.

1,112,977.

Specification of Letters Patent.

Patented Oct. 6, 1914.

Application filed May 20, 1914. Serial No. 839,734.

To all whom it may concern:

Be it known that we, HENRY A. CARPENTER and ARTHUR W. WARNER, citizens of the United States, residing at Sewickley, in the county of Allegheny and State of Pennsylvania, have invented certain new and useful Improvements in Closure-Locking Means for Gas-Retorts, of which the following is a specification.

10 The operation of coal gas generating apparatus as heretofore constructed is sometimes interrupted and seriously retarded by prematurely opening a retort. With the front and rear closures under separate control, and with the operatives necessarily separated by the length or depth of the bench, communication between them cannot be readily maintained, and even with every precaution as to signaling from one 20 to the other, the fallible human element has always been present and has resulted in more or less frequent premature opening of the retort, particularly at its rear.

One object of the present invention is to 25 provide for so controlling the closures at the front and rear ends of the retort that it is impossible to prematurely open either closure, the arrangement being preferably such that opening of the rear end closure is 30 controlled by the front end closure, the opening movement of the latter effecting the release of the closure at the rear end.

A further purpose is to so coördinate the 35 retort closures with the valve which controls communication between the retort and the stand pipe that the valve is necessarily seated before either closure can be opened.

A desirable adaptation consists of an 40 index device that is in the path of a closure latch mechanism and which when moved sufficiently to clear the latch results in seating the valve. This coördination renders it impossible to admit atmospheric air at either end of the retort in advance of closing communication with the gas offtake.

In the accompanying drawings, Figure 1 is a view in sectional plan of the charging and discharging ends of a gas retort and the closures therefor, the latter being shown 50 closed in full lines and open in dotted lines. Fig. 2 is a front elevation of the closure at the discharge end of the retort, and Fig. 3 is a side or edge view of the same. Fig. 4 is a front elevation of the closure at the charg-

ing end of the retort, and Fig. 5 is a side 55 or edge view thereof. Fig. 6 is an elevation of the circuit interrupting mechanism which is operated by the charging closure door, a portion of the inclosing casing being removed. Fig. 7 is a sectional elevation, taken 60 on the broken lines 7—7 of Fig. 6. Fig. 8 is a sectional plan taken on line 8—8 of Fig. 7. Fig. 9 is a detail view of the shoe for imparting opening pressure to the circuit breaker. Fig. 10 is a sectional elevation of 65 the locking mechanism for the discharge closure, taken on line 10—10 of Fig. 13. Fig. 11 is a sectional detail on line 11—11 of Fig. 10, and Fig. 12 is a vertical cross-section taken on line 12—12 of Fig. 10. 70 Fig. 13 is a plan view of the lock mechanism at the retort discharge, the upper portion of the inclosing casing being removed.

Referring to the drawings, 2 designates 75 one of a series of retorts of a gas bench; 3 is the mouth piece at its inlet or charging end of the retort, and 4 the mouth piece at its outlet or discharge end. Mouth piece 3 is enlarged at one side at 5 with port 6 80 thereof communicating with the gas off-take or stand-pipe 7. Valve 8 for controlling communication with the off-take is adapted to be operated at the front of the mouth piece through the medium of rock 85 shaft 9 which may be rotated in any suitable manner. This shaft carries the index arm 10 which, when the valve is open as in full lines in Figs. 1 and 4, projects into the path of the swinging latch mechanism 15 90 for the front end closure when the latter is in closure-confining position. This latch mechanism may serve to close the valve, movement of said mechanism in a direction to release the closure serving to turn the 95 index arm 10 and thereby rock the shaft 9 and close the valve.

As illustrating an embodiment of the present invention, the closure for the charging end of the retort is indicated as 11 and 100 its hinged bar-like support as 12, while at the discharge end the closure bears reference numeral 13 which is carried by hinged bar 14. The free end of bar 12 is confined by a laterally swinging latch mechanism 15, 105 and a similar mechanism 16 performs the same function for bar 14 of the discharge closure. A horizontally swinging arm 17

2

controls the manipulation of bar 12 necessary for releasing latch mechanism 15, and arm 18 similarly controls the discharge closure bar 14. When arm 17 is turned from the position shown in Fig. 1, eccentric 17' at its pivoted end moves support 12 toward closure 11 so that latch mechanism 15 may be readily turned to release the bar, and eccentric 18' performs the same service for bar 14 with reference to rear end closure 13 when arm 18 is turned into position for releasing latch 16. Arm 18 is disposed toward the hinged end of support 14 when said closure is closed, while at the charging end 15 the swinging arm 17 for hinged support 12 is disposed toward the free end of the latter when closure 11 is in closed position.

For so connecting the charging and discharging closures that the latter cannot be opened in advance of the former, a mechanism is interposed which at the charging end is operated by the movement of the hinged closure support 12, and at the discharge end coöperates with swinging arm 18, the latter being held locked as indicated in full lines in Figs. 1, 2 and 10, until the front closure has been opened. While there is no impediment to the movement of arm 17 of the charging closure from the position shown in Fig. 4 and in full lines in Fig. 1 to the open dotted position of Fig. 1, support 12 cannot be released from its latch device 15 until index arm 10 is moved out of way of the latter and this can only be accomplished by closing valve 8 so that it is mechanically impossible to swing support 12 to open position before closing the off-take valve.

The mechanism for connecting the front and rear closures for insuring their opening in proper sequence may be variously arranged. As here embodied that mechanism includes an electric motor device for actuating the discharge closure lock, together with a switch for the circuit of said device which is operated by the movement of the inlet or charging closure.

The lock device for arm 18 of discharge closure 13 consists of an arm 19 which is forked at 20 to embrace arm 18 when the latter is in closed position, as shown in full lines in Figs. 1 and 10, arm 20 being secured to rock shaft 21 journaled in a casing 22 secured by bracket 23 to mouth piece 4. Secured to shaft 21 within said casing is arm 25 which when raised holds arm 18 from swinging outward into releasing position. Arm 25 is held elevated by the notched upright arm 26 of bell-crank 27, the latter fulcrumed at 28 in casing 22, with the horizontal arm of the lever entered in a slot in core 29 of solenoid 30. With the solenoid de-energized, its core drops by gravity and thereby moves and holds bell-crank 27 in the full line position of Fig. 12 with its notched vertical arm 26 beneath and holding raised

arm 25. With the solenoid energized, its core is elevated and bell-crank 27 rocked into the dotted line position of Fig. 12, thereby releasing arm 25 and permitting the forked arm 20 to oscillate in response to the outward pull on the closure unlocking arm 18 so that closure 13 may then be opened.

The energy for the coil of solenoid 30 is controlled by a circuit having leads 31 and 32 which extend to the front of the retort and into a casing 33 which incloses a circuit breaker. This casing may be secured by bracket 34 to mouth piece 3. Within the casing lead 31 is secured to contact plate 35, and lead 32 to contact plate 36. Plates 35 and 36 are adapted to be connected by the circuit closing (or breaking) arm 37 which near one end is mounted to oscillate on bolt 38, with a spring 39 confined on the bolt and exerting pressure on the arm to move it into closed position. One extremity of arm 37 is in constant engagement with contact 36, Figs. 6 and 8, while its free end carries the rounded contact shoe 40 for engaging contact 35.

The circuit breaker 37 is engaged by the insulated shoe 41 carried by the free end of arm 42. The latter is secured to shaft 43 within casing 33, and an arm 44 on said shaft at the exterior of the casing has its laterally bent extremity 45 adapted to be engaged by the swinging support 12 of the front or charging closure 11.

When support 12 and closure 11 are in retort closing position shown in Figs. 1 and 8, arm 44 is pressed inward and the circuit breaker 37 is held in open position by arm 41 notwithstanding the pressure of spring 39. But as soon as support 12 swings into open position, spring 39 moves shoe 40 of arm 37 into engagement with contact 35 and closes the circuit through leads 31 and 32. This results in energizing solenoid 30, and the upward movement of its core tilts the bell-crank latch 27 and releases the lock for arm 18 of the discharge end closure, whereupon the latter may freely open. But prior thereto the closure 13 is held securely locked and it is quite impossible to open it in advance of opening the front end or charging closure 11. And as the latter cannot be opened until communication is closed between the retort and off-take, it will be seen that the sequence of operations is relieved of the uncertainties of human control, the several elements being so connected as to insure their operation in proper sequence.

When sealing up the retort, the rear closure 13 may be closed either before or after the front closure 11. Fork 20 in the open position shown in dotted lines in Fig. 10 is adapted to receive arm 18 as the latter moves to closed position, and the resulting oscillation of arm 19 raises arm 25. If the front

closure 11 has been closed first and the solenoid deenergized, arm 25 simply deflects and is then secured by latch 27.

What we claim is:—

5. 1. The combination of a gas retort, closures for opposite ends of the retort, mechanism for locking one of the closures in closed position, and lock-releasing mechanism operatively connected to the other closure.
  10. 2. The combination of a gas retort, a closure for the rear end thereof, locking mechanism for securing said closure in closed position, a closure for the front end of the retort, and means actuated by the opening movement of the front end closure for unlocking the rear end closure.
  15. 3. The combination of a gas retort, a closure for the rear end thereof, mechanism for locking said closure in closed position, a closure for the front end of the retort, operating means for the front end closure, and means actuated by the opening movement of the front end closure operating
  20. 25. means for unlocking the mechanism which secures the rear end closure.
  4. The combination of a gas retort, closures for the opposite ends thereof, an electrically operated device for locking one of said closures in closed position, a circuit for said device, and a controller for the circuit adapted to be actuated by the opening and closing movements of the other closure.
  30. 5. The combination of a gas retort, a closure for the rear end thereof, a locking device for said closure, an electrical device adapted to control the locking device, a circuit for said electrical device, a closure for the front end of the retort and a circuit controlling device operatively connected to and actuated by the movements of the front end closure.
  35. 6. The combination of a gas retort, a closure for the rear end thereof, means for locking said closure in closed position, an electrically operated device adapted when energized to release said locking mechanism, a circuit for said device, a closure for the front end of the retort, a circuit breaker in said circuit, and means operatively connecting the circuit breaker and the front end closure whereby the opening movement of the latter moves the breaker to circuit
  40. 55. closing position.
  7. The combination of a gas retort, an off-take conduit in communication therewith, a valve controlling such communication, closures for the opposite ends of the retort, and means interposed between and operatively connecting the valve and said closures whereby neither closure can be opened in advance of closing said valve.
  60. 8. The combination of a gas retort, an off-take conduit in communication there-
- with, a valve for controlling such communication, closures for opposite ends of the retort, operating means for one of the closures, actuating means for said valve adapted to hold said closure operating means in closed position so long as the valve is open, and an operative connection between the valve-controlled closure and the other retort end closure whereby the latter is held in closed position until after the valve controlled closure has been opened.
9. The combination of a gas retort, a closure for the rear end thereof, an operating lever for the closure, a lock device for securing said lever when the closure is in closed position, electrically actuated lock operating means including an electric circuit, a closure for the front end of the retort, and a controlling device for said electric circuit operatively connected to and actuated by the movement of the front end closure.
10. The combination of a gas retort, a closure for the rear end thereof, an actuating lever for the closure, a movable lock device for securing the lever with said closure in closed position, said device adapted to move by gravity to locking position, an electrical device adapted when energized to move the latter device into released position, a closure for the front end of the retort, and means operatively connected to and actuated by the movement of the front end closure for passing current to said electrical device.
11. The combination with a gas retort, a closure for the rear end thereof, an actuating lever for the closure, a locking lever adapted to engage the first mentioned lever and secure it in inoperative position, a latch for controlling the movement of the locking lever, a closure for the front end of the retort, and means actuated by the opening movement of the front end closure for operating said latch.
12. The combination with a gas retort, a closure for the rear end thereof, an operating lever, a locking lever forked to embrace the operating lever, a latch adapted to engage the locking lever, a solenoid having its core operatively connected to said latch, a circuit for the solenoid, a closure for the front end of the retort, and a circuit controlling device operatively connected to and actuated by the opening and closing movements of the front end closure.
13. The combination of a gas retort, a closure for the front end thereof, an electrical circuit and circuit breaker, a movable device operatively connected to the circuit breaker and to the retort closure and positioned by the latter when closed to open the circuit breaker, a closure for the rear end of the retort, and an electrically operated lock device adapted to retain the

rear end closure in closed position so long as said circuit is open.

14. The combination of a gas retort, a closure for the front end thereof, an electric circuit, circuit closing and opening means operatively connected to and actuated by the opening and closing movements of the retort closure, a closure for the rear end of the retort, a device for locking the rear end closure in closed position, and electrical

means in said circuit for actuating the locking device.

In testimony whereof we affix our signatures in presence of two witnesses.
